CURTAIN AND DRAPERY HANGER FOR
WINDOWS

George B. Yerton, New York, N. Y.

Application June 10, 1940, Serial No. 339,643

2 Claims. (Cl. 248—263)

This invention relates to curtain and drapery hangers for windows.

An object of this invention is to provide a curtain and drapery hanger of the character described, which shall be relatively easy to mount on a window and simple to adjust as to height and width, and in which the curtain rod may be mounted at a different height from the drapery rod.

Another object of this invention is to provide a strong and durable hanger of the character described, which shall be relatively inexpensive to manufacture, attractive in appearance, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a front elevational view of the upper portion of a window frame provided with drapery and curtain hangers embodying the invention;

Fig. 2 is a top plan view of the structure shown in Fig. 1;

Fig. 3 is an enlarged cross-sectional view taken on line 3—3 of Fig. 2;

Fig. 4 is an enlarged cross-sectional view taken on line 4—4 of Fig. 2;

Fig. 5 is a view similar to Fig. 2, but illustrating a modified construction.

Referring now in detail to the drawing, 10 designates a window frame provided with drapery and curtain hangers 12 embodying the invention. The window frame has side portions 13 and a top portion 14. The side portions 13 of the window frame have outer surfaces 13a and the top portion 14 has a top surface 14a.

Fixed to the upper corners of the window frame 10, are a pair of similar, symmetrically disposed brackets 20. Each bracket 20 has a vertical wall 21 contacting the outer surface 13a of one of the window frame portions 13, and formed with an opening for a screw 21b adapted to be screwed into the window frame. Extending at right angles to portion 21 is a portion 22 contacting the top surface 14a of the window frame portion 14. On portions 21 and 22 are prongs 21a and 22a, 55

respectively, adapted to dig into the window frame to help hold the bracket on the frame.

Portions 22 of the bracket has a screw threaded opening to receive a screw 25 screwed into the window frame to fix the bracket to the frame.

Extending from wall 21, at right angles to the walls 21 and 22, is a wall 26 formed with a pair of vertical rows of spaced key openings 28. Mounted on the brackets 20 is a curtain rod 29 and a drapery or portiere rod 30. The curtain rod 29 may be in the form of a two part extensible curtain rod of any construction. The parts 29a each have a rearwardly extending foot 33 formed with a rearwardly extending horizontal stem or neck 34 formed with a head or ball 35. The heads 35 are passed through the enlarged portions of the key openings to permit the curtain rod 29 to be slidably moved downwardly to engage the necks 34 within the narrow portions 20 of the key openings.

The drapery or portiere rod 30 is likewise a two part extensible member, and each part 30a has a rearwardly extending foot 36 formed with a rearwardly extending horizontal stem or neck 37 provided with a knob, ball or head 35 at its rear end. The portiere or drapery rod 30 is mounted on the brackets 20 in the same manner as the curtain rod.

It will be noted, however, that the rod 30 is mounted in the outer row of key slots 28, whereas, the curtain rod 29 is mounted on the inner row of key slots. The rods may be mounted in any desired adjusted height.

In Fig. 5 there is shown a bracket 20a, illustrating a modified form of the invention. The bracket 20a differs from the bracket 20 in that the wall 26a formed with key slots extends inwardly instead of outwardly and is spaced in front of the window frame as shown in Fig. 5 of the drawing. Furthermore, the curtain and drapery rods may be formed with collars 40, adjacent the stems 34 and adapted to contact the front faces of bracket walls 26a.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A structurally integral, one-piece bracket of the character described comprising a wall having a prong, a second wall of less width than the first wall extending from the upper edge of and adjacent the rear portion of the latter and at right angles to the first wall, said second wall also having a prong, both of said walls having openings to receive fastening elements to fasten the bracket to a window frame, said bracket further comprising a third wall extending from the forward edge of the first wall and at right angles to the first and second walls, said third wall having a plurality of spaced, vertical rows of spaced key slots adapted to be selectively engaged by curtain rods, said third wall extending in the same direction from the first wall as the second wall and being spaced forwardly of the latter.

2. A structurally integral, one-piece bracket of the character described, comprising a wall having a prong, a second wall of less width than the first wall extending from the upper edge of and adjacent the rear portion of the latter and at right angles to the first wall, said second wall also having a prong, both of said walls having openings to receive fastening elements to fasten the bracket to a window frame, said bracket further comprising a third wall extending from the forward edge of the first wall and at right angles to the first and second walls, said third wall having a plurality of vertical rows of spaced key slots adapted to be selectively engaged by curtain rods, said third wall being spaced forwardly of the second wall.

GEORGE B. YERTON.
